UNITED STATES PATENT OFFICE.

JOHN F. O'CONNOR, OF CHICAGO, ILLINOIS, ASSIGNOR TO W. H. MINER COMPANY, OF CHICAGO,
ILLINOIS, A CORPORATION OF ILLINOIS.

DRAFT-RIGGING FOR RAILWAY-CARS

No. 902,903.

Specification of Letters Patent.

Patented Nov. 3, 1908.

Application filed May 4, 1907. Serial No. 371,784.

To all whom it may concern:

Be it known that I, JOHN F. O'CONNOR, a citizen of the United States, residing in Chicago, in the county of Cook and State of Illinois, have invented a new and useful Improvement in Draft-Rigging for Railway-Cars, of which the following is a specification.

My invention relates to improvements in draft rigging for railway cars in which the spring of the draft rigging operates also to center the draw-bar, and more particularly to improvements upon the draft rigging of this kind heretofore patented to me in my Letters Patent No. 829,731 of August 21st, 1896.

The object of my present invention is to simplify and improve the construction of my said patented draft rigging and materially shorten the draw-bar, while securing all the advantages and accomplishing all the results of my previously patented construction.

My invention consists in the novel construction of parts and devices, and in the novel combinations of parts and devices herein shown and described, and more particularly specified in the claims.

In the accompanying drawing forming a part of this specification, Figure 1 is a side elevation partly in central vertical longitudinal section, of a draft rigging having a draw-bar centering mechanism embodying my invention. Fig. 2 is a plan view. Fig. 3 is a central, vertical, longitudinal section on line 3-3 of Fig. 2. Fig. 4 is a horizontal section on line 4-4 of Fig. 1. Figs. 5 and 6 are vertical cross sections on lines 5-5 and 6-6 of Fig. 3 and Fig. 7 is a detail plan view of the draw-bar centering block.

In the drawings, A represents the center sills or frame pieces of the car to which the side plates or stop castings B of the draft rigging are secured.

C C¹ are tandem arranged springs, D D the followers, E the draw-bar yoke or extension, F the draw-bar, G the draw-bar centering block, H H thimble blocks and K K¹ the connecting rivets.

The draw-bar F is provided with a pair of integral laterally projecting rocker or pivot arms f, one projecting to each side of the front rivet K about which as a center the draw-bar turns in its laterally rocking or swinging movements. The draw-bar cen-

tering block G which is interposed between the rear end of the draw-bar and the front follower D is provided on each side with seats or bearings g fitting and engaging the rounded end f¹ of the rocker arms f of the draw-bar.

The draw-bar centering block G is provided with two longitudinally extending slots or elongated openings g¹ g² in which fit the thimbles h h¹ of the thimble blocks H H. The draw-bar F is provided with upper and lower pivot ears f² f³ separated by a horizontal slot f⁴ in which fits the central pivot lug g³ of the draw-bar centering block G. The pivot ears f³ on the draw-bar have circular openings f⁵ therein in which fit the front thimbles h h of the thimble blocks H H. The front connecting rivet K extends through the draw-bar yoke E and the pivot ears of the draw-bar and through the front thimbles h h of the thimble blocks H H, and also through the pivot lug g³ of the draw-bar centering block G, thus connecting all these parts. The rear connecting rivet K¹ extends through the draw-bar strap or yoke E, the rear thimbles h¹ h¹ of the thimble blocks H H and also through the rear opening g² of the draw-bar. The draw-bar centering block G is thus, by the front and rear or double thimbles h h¹ on the thimble blocks H H and the front and rear rivets K K¹, directly and immovably connected to the draw-bar yoke E so far as the longitudinal movement of the one in respect to the other is concerned, while permitting of a limited lateral play governed by the longitudinal slots in the draw-bar connecting block G. And as the transverse dimension of the front and rear slots g¹ g² equals the diameter of the cylindric thimbles h h¹, the block G can have no lateral play in respect to the yoke E. And at the same time, the draw-bar F is pivotally connected to the yoke E, as well as to the draw-bar centering block G and prevented from having any longitudinal movement in respect to the yoke E.

And the lengthwise extending slots g¹ g² permit the draw-bar centering block G to have a slight longitudinal movement in respect both to the draw-bar and to the draw-bar yoke under action of the draw-bar spring and front follower so that when the draw-bar swings to one side or rocks laterally, the draw-bar spring will be slightly compressed by reason of the interengaging rocker arms

f and rocker seats *g*, and consequently causes the draw-bar to be restored to its central position when the spring expands.

By this novel construction and co-operative combination of parts, I thus avoid the necessity of providing any transversely extending slots or transversely elongated openings either in the draw-bar, the draw-bar yoke or in the longitudinally movable draw-bar centering block, and thereby add materially to the strength and durability of the draft rigging as well as simplify its construction.

I claim:—

A draft rigging and draw-bar centering mechanism consisting in the combination with the draw-bar, draw-bar-yoke, spring, follower, the draw-bar being provided with lateral rocker arms and upper and lower pivot ears furnished with circular openings through the same, a draw-bar centering block

having longitudinal slots through the same and provided with lateral seats engaging the rocker arms on the draw-bar, a pair of thimble blocks having front and rear thimbles, the front thimbles extending through the pivot ears of the draw-bar and fitting in the central pivot lug of the draw-bar-centering block and the rear thimbles on said thimble blocks fitting in the rear slot in said draw-bar centering block, and front and rear connecting rivets extending through the draw-bar-yoke and said thimbles of the thimble blocks, the portion of the draw-bar in front of said front connecting rivet being imperforate substantially as specified.

JOHN F. O'CONNOR.
